CLAIM

I claim the solar panel clip for irrigation hose, as shown and described.

DESCRIPTION

FIG. 1 is a perspective view of a solar panel clip for irrigation hose, showing my new design;

FIG. 2 is a front view of FIG. 1;

FIG. 3 is a rear view of FIG. 1;

FIG. 4 is a right side view of FIG. 1, a left side view being a mirror image;

FIG. 5 is a top view of FIG. 1; and,

FIG. 6 is a bottom view of FIG. 1.
